UNITED STATES PATENT OFFICE.

WILLIAM WASHINGTON AYRE, OF BROOKLYN, NEW YORK.

GAME.

1,420,400.

Specification of Letters Patent. Patented June 20, 1922.

Application filed April 26, 1921. Serial No. 464,635.

To all whom it may concern:

Be it known that I, WILLIAM W. AYRE, a citizen of the United States, residing at Brooklyn, in the county of Kings and State 5 of New York, have invented certain new and useful Improvements in Games; and I do hereby declare the following to be a full, clear, and exact description of the invention, such as will enable others skilled in 10 the art to which it appertains to make and use the same.

This invention relates to games and has more particular reference to an educational electrical game.

15 The objects of the invention are to provide a game which will promote interest in electrical devices; to employ electrical terms and representations of electrical devices; to make the player associate the electrical 20 terms with the representation of the electrical devices; to associate the terms and devices with appropriate rooms of a house; to permit the game to be easily understood, to render it enjoyable as well as instructive, to 25 obtain a structure which is cheaply manufactured and attractive in appearance, and to obtain other advantages and results as may be brought out in the following description.

30 Referring to the accompanying drawing in which like numerals of reference indicate the same parts throughout the several views.

Figure 1 is a plan or face view of the body portion or game proper.

35 Figure 2 is a view showing several of the movable members, and

Figure 3 is a face view of the spinner for use with the game.

In the specific embodiment of the invention illustrated in said drawing, the reference numeral 1 indicates the body portion 40 of the game, which may be of paper, cardboard, or any other suitable material as found desirable or best fitted for the purpose 45 for which it is used. This body portion 1 bears upon its face the floor plan 2 of a house. This floor plan may be printed or otherwise permanently fixed to the body portion 1, and for convenience the representation 50 of the several rooms are designated as "bed room, dining room, laundry" and so forth, so the players will recognize what each room is intended to be. In each room I prefer to indicate certain electrical 55 devices which may be used in that particular room. As one mode of designation, I have

shown words 3 such as "ozonator, heating pad, vibrator" and so forth, written upon the floor plan of the house. These designations are furthermore included in the 60 present disclosure within circles 4, each designation of an electrical device being within a separate circle.

Movable members 5 are provided for placing upon the body portion by the player, 65 and these movable members also preferably have designations 6 of electrical devices corresponding to the designations 3 on the body portion of the game. By preference, however, the designations 3 on the body portion and the designations 6 on the movable member differ in character from each other, the one being shown as the words and the other being shown as a representation or picture of the article. It perhaps makes the 70 game more realistic to have the representation or picture on the movable members and the words on the body portion, since the words more closely indicate the lack of the article and express its need which is filled 75 by bringing in the representation. The game therefore includes associating in the player's mind the picture or representation 6 with the word or designation 3, and when he goes to place one of the movable members 80 upon the body portion it is necessary to recognize the representation by its appropriate name. Obviously, while I have shown the picture as upon the movable member and the designation as upon the body portion, it is to be understood that this might 85 be reversed without departing from the present invention. Preferably the circles 4 are provided so as give room with each designation 3 for the movable member 5 to be 90 placed without interfering with other designations.

In combination with the body 1 and the movable members 5, I preferably provide a spinner 7 having a rotatable pointer 8 and 100 having designations 9 of electrical devices to which the pointer 8 may be spun. There are at least as many designations 9 upon the spinner as there are designations 3 upon the body 1. In the present disclosure I have 105 shown some of the designations duplicated upon the spinner which will increase the difficulty of the players in winning the game. There should be as many of the movable members 5 as there are designations 3 upon 110 the body portion.

In use, the players successively spin the

pointer 8 and when it stops upon a particular designation of an electrical device the player then chooses the proper movable member 5 and places it upon the proper designation 3 of the body portion 1. Each member so placed gives the player credit for a certain number of points. These may be variable or may all be the same as found desirable in playing the game, and the credit 5 may be indicated at any suitable part of the game either in the directions, upon the designations or elsewhere as found the most desirable in the manufacture and use of the game. Should the spinner stop upon a 10 designation of which the movable member has already been placed upon the board the player may be penalized or if preferred the penalty may be attached after the player is 15 unable to play for this reason after a plurality of attempts. The invention is not restricted to these particular rules, they being referred to merely for suggesting one definite way in which to play the game. An important rule to include would seem to be 20 that the wrong selection of a movable member or the wrong selection of the designation where the movable member is placed would severely penalize the player. Such a rule would necessitate care in the choice and positioning of the movable members and would 25 encourage the players to promptly become acquainted with the various devices with 30 which they are playing.

In order to better acquaint the players 35 with the devices and perhaps to describe the same from their utility standpoint, the various devices may be illustrated in the margin of the body portion, as shown at 10, and suitable descriptive matter 11 associated 40 with the representations 10.

Other modifications, changes and variations in the manufacture and use of my invention may be made without departing from the spirit or scope of the invention, 45 and I do not wish to be understood as limiting myself except as required by the following claims when construed in the light of the prior art.

Having thus described my invention, I claim.

1. In a game of the character described, the combination of designations of electrical devices, and movable members for association therewith by the player having other designations of the same devices thereon, one 55 of said designations being words and the other designation being pictures.

2. In a game of the character described, the combination of a body portion having word designations of electrical devices thereon, and movable members having corresponding picture designations of said electrical devices thereon whereby the player has to associate the picture designation with the word designation in placing the movable member on said body portion.

3. In a game of the character described, the combination of a body portion having the floor plan of a house thereon, designations of electrical devices in the several 70 rooms of the floor plan, and movable members having corresponding electrical designations thereon.

4. In a game of the character described, the combination of a floor plan having 75 designations of electrical devices thereon, movable members each having the designations of an electrical device thereon corresponding to one of the designations on the floor plan, the designations on the floor plan 80 and on the movable members being one word designations and the other picture designations whereby the player has to associate the proper picture with the corresponding word.

5. In a game of the character described, the combination of a plurality of designations of electrical devices, movable members having corresponding designations thereon, and a spinner also having designations of 90 the same electrical devices, the designations of one of said parts differing in character from the designations on the other part.

In testimony whereof I affix my signature.

WILLIAM WASHINGTON AYRE.
